UNITED STATES PATENT OFFICE.

BURT A. PETERSON, OF ROCKFORD, ILLINOIS, ASSIGNOR TO BARBER-COLMAN COMPANY, OF ROCKFORD, ILLINOIS, A CORPORATION OF ILLINOIS.

SPOOLING PROCESS.

Original application filed September 11, 1919, Serial No. 323,194. Divided and this application filed October 22, 1923. Serial No. 669,893.

The spooling process as practiced in cotton mills consists in unwinding a succession of supply yarn masses, the yarn or thread of said yarn masses being wound upon a spool 5 or cheese core. The supply yarn masses have heretofore ordinarily been bobbin on which yarn has been wound in the manner known as "warp wind", that is to say, the yarn was traversed up and down the bobbin while the 10 yarn was being wound thereon, the traverse being gradually shortened at both ends of the bobbin as the yarn mass increased in diameter. These warp-wound bobbins were placed in bobbin-holders virtually constituting pock- 15 ets in which the bobbins lay upon their sides, the yarn being unwound from the side of the bobbins, and the bobbins being thus caused to revolve. The speed at which the yarn could be unwound was limited by the 20 weight of the bobbin and its liability to jump in the bobbin-holder. This manner of supporting and unwinding the supply yarn masses necessarily imposed considerable tension upon the yarn.

25 Another method of unwinding which has been practiced to a slight extent consisted in using filling-wound bobbins, that is to say, bobbins upon which the yarn had been wound with a relatively short traverse and 30 constant "gain", the yarn being laid upon the bobbin in superposed layers of conical form. When such a bobbin was employed in the spooling process, it was stationarily supported by its butt end, the yarn being 35 drawn off the tip of the bobbin. The speed at which such a bobbin could be thus unwound was limited by the tendency of the yarn to form kinks which passed to the spool or cheese and caused trouble in the subse- 40 quent process of unwinding the yarn from the spools onto a warp beam. The speed attainable in spooling was also further limited by the tendency of the before-mentioned conical layers to come off the bobbin in a 45 bunch or tangle which stopped at the thread guide and caused the running thread to break. The method of unwinding yarn which involves the drawing of the yarn off the end of filling-wound bobbins, while de- 50 sirable by reason of the low tension placed upon the yarn, has therefore proved impracticable at relatively high speeds.

I have discovered that a warp-wound bobbin can be successfully unwound from the end thereof, providing the unwinding speed 55 is sufficiently great, and, by employing this method, have attained a speed in spooling which is quite extraordinary.

Referring now to the accompanying drawing which is a fragmental left-hand side 60 view of a winder by means of which the process may be practiced: The bobbin *a* is supported upon a skewer 17 engaging the butt of the bobbin. The yarn *F* is shown as being drawn off the upper end of the bobbin, the yarn passing through the detector *B*, or other suitable guide means, and thence to a cam drum *D* for supporting and rotating the cheese *E* and traversing the yarn *F*. The bobbin *a* is an ordinary warp bobbin 70 having a warp-bound yarn mass thereon. When the cheese *E* is revolved at high speed, the yarn balloons and thus swings clear of the yarn mass and the tip of the bobbin, even when the unwinding thread 75 extends from the lower portion of the yarn mass.

By using warp-wound bobbins and unwinding the yarn thereof from the end of the bobbin several very desirable ends are 80 attained, namely, high speed with consequent high production, spooling under low tension, the prevention of kinking and reduced yarn breakage. Experience has shown that there is less breakage in unwinding 85 warp-wound bobbins at 1200 yards per minute than in unwinding filling-wound bobbins at 400 yards per minute.

This application is a division of my application Ser. No. 323,194 filed September 90 11, 1919.

I claim as my invention:

A spooling process which includes stationarily supporting a warp-wound bobbin by its butt end and drawing the yarn off the 95 end of the bobbin at such high speed that the yarn balloons clear of the yarn mass and the tip of the bobbin.

In testimony whereof, I have hereunto affixed my signature.

BURT A. PETERSON.
